CLAIM

The ornamental design for a wrist wrap, as shown and described.

DESCRIPTION

FIG. 1 is a front perspective view of a wrist wrap showing my new design, with the thumb and fingers of a wearer shown in broken lines and forming no part of the claim;

FIG. 2 is an upper right rear perspective view thereof, with the thumb and fingers of a wearer again shown in broken lines and forming no part of the claim;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a top plan view thereof;

FIG. 8 is a bottom plan view thereof;

FIG. 9 is a front elevational view thereof in an unwrapped, flat state;

FIG. 10 is a right side elevational view thereof in an unwrapped, flat state;

FIG. 11 is a rear elevational view thereof in an unwrapped, flat state;

FIG. 12 is a left side elevational view thereof in an unwrapped, flat state;

FIG. 13 is a top plan view thereof in an unwrapped, flat state; and,

FIG. 14 is a bottom plan view thereof in an unwrapped, flat state.
